UNITED STATES PATENT OFFICE

SEWARD R. SEYBOLD, OF NEW KENSINGTON, PENNSYLVANIA.

WINDOW SHADE AND CURTAIN BRACKET.

No. 888,356.

Specification of Letters Patent.

Patented May 19, 1908.

Application filed March 18, 1907. Serial No. 362,869.

To all whom it may concern:

Be it known that I, SEWARD R. SEYBOLD, a citizen of the United States, residing at New Kensington, in the county of Westmoreland 5 and State of Pennsylvania, have invented certain new and useful Improvements in Window Shade and Curtain Brackets; and I do hereby declare the following to be a full, clear, and exact description of the invention, 10 such as will enable others skilled in the art to which it appertains to make and use the same.

For window shades and curtains I have produced an improved bracket of the kind in which the pair is fastened by integral tangs 15 driven into the window casing and the bracket maintained in its fastened position by a coiled spring fixed at one end to the bracket and terminating at its other end in a hook or pin adapted to engage the casing by 20 driving or hooking and to exert a pulling clamping force on the bracket to hold its fastening tangs securely and firmly in the casing. Each bracket with its own fastening spring for this purpose is secured under tension to that part of the casing to which the bracket is fastened, whereby the brackets 25 can be quickly and easily secured to the casing in their proper relative positions without nails or screws and as quickly removed, the 30 clamping spring of each bracket being fastened to the casing at a point opposite to the fastening tangs.

The arrangement of the tangs on the fastening member of the bracket whereby they 35 sustain the bracket vertically and against the tendency to droop under the weight of the shade, the curtain and their supports on the overhanging members, is also a feature of my invention and in the claims appended 40 hereto I will point out the precise improvement in connection with the accompanying drawings in which,—

Figure 1 represents a front view of a portion of a window casing with my improved 45 shade and curtain brackets applied thereto. Fig. 2 shows in perspective one of the shade and curtain holding brackets and its clamping spring. Fig. 3 is an identical view with the adjustable slide of the shade roller supporting member in reversed position and 50 without the pole bearing arm. Fig. 4 shows the blank from which the shade and curtain bracket is produced. Fig. 5 shows in section one of the brackets showing its tangs and the 55 clamping spring fastened to the casing.

The blank is preferably stamped out of heavy sheet steel and subsequently formed into a bracket having an upper horizontal arm 1, for supporting the curtain or drapery pole 2, a depending supporting bar 3, by 60 which the bracket is secured to the window frame or casing, and a horizontal arm 4, for supporting as well as suspending a shade roller supporting slide. The pole supporting arm is twisted to form a concave outer end 65 to provide a confining seat 5, for the curtain-pole, said arm 1 extending at right angles with respect to the arm 4.

The depending bar has a plurality of punched out tangs or prongs 6, in the middle 70 of its length which, when driven into the window casing, support the bracket vertically. The shade roller supporting arm 4, extends from the inner edge of the lower end of the depending fastening bar at right 75 angles to the pole supporting arm and is provided with the slide 7, from one end of which a right angled arm 8, projects and forms the support for the curtain roller. A brace 9, strengthens the connection of this 80 curtain roller supporting arm with the depending bar at their junction. The slide is fitted upon the arm by groove forming lips 10, by which it is made adjustable to adapt it to different lengths of curtain-rollers; and 85 to increase this capacity for the adjustment of the slide it is made reversible so that its roller supporting arm may be set in one position toward the end of the arm for long rollers, as in Fig. 2, or be reversed and set next 90 to the depending fastening bar as in Fig. 3, making the adjustment within the range of about six inches for different widths of shades. For this purpose one of the groove forming lips of the slide is shorter than the 95 other to allow the slide to be set up against the edge of the brace when its roller bearing arm is set up next the depending fastening bar for short curtain rollers. The tangs or 100 prongs while supporting the device by its depending bar vertically, the weight of the pole, its curtains, and of the shade hanging parts including the downward pulling force on the shade to unwind its spring roller, tend 105 to pull down the ends of the overhanging arms and to loosen the hold of the fastening tangs. To prevent this and to provide additional fastening means for the device tangs or prongs 11, are struck out at the outer edge 110 of the depending bar in the operation of pro-

ducing the blank and subsequently upset so as to stand inward between the middle row of prongs, whereby the flat sides of the middle row of tangs stand upward and the flat 5 sides of the edge row of tangs stand inward between the middle tangs and reinforce the holding function of the depending bar. It will be understood that these brackets are in pairs and adapted for use with spring 10 rollers and may be very cheaply produced and fastened in place both sets of the fastening tangs being driven at the same time.

While the arrangement of the tangs support the bracket in the two directions stated 15 its tangs are nevertheless liable to become loose by the jar and strain in unwinding and winding the spring-roller of the shade and to fail in a firm hold in the casing and to prevent this I provide means carried by 20 each bracket and fastened in the casing whereby the tangs are safely and firmly maintained in the casing. For this purpose a coiled spring 12, is attached by one end to an eye on the fastening or tang member of the 25 bracket and terminates at its other end in a hook or pin 13, by which it is fastened by hooking or pin driving into the casing at a point at the side of the bracket opposite the tangs, so that the clamping spring being 30 thus held under a strong tension exerts its force to pull and firmly hold the tangs of the fastening member into the casing. For this purpose the hook or pin of the clamping spring can be driven into the face of the casing 35 or into its inner vertical edge and thus each bracket is provided with its own safety clamping spring fastened to the casing at the same time the tangs are driven into the outer edge of the casing and both fastenings 40 for the bracket made easily and quickly and in which both the tangs and the spring can be separated from their hold in the casing when it is desired to remove the bracket.

An important advantage of connecting the 45 spring of each bracket directly to that part of the window casing to which the bracket is secured is that it allows the use of a separate short spring for each bracket and of attaching the fastening end of each spring to that 50 side of the vertical casing bar opposite to that side of the bracket which has the fastening tangs. In such attachment of each spring its hook end can be fastened over the edge of the casing and stretched to give it 55 the desired strong tension to hold the driven tangs firmly in the casing; and this capacity for stretching the spring adapts its attaching sharp end to be fastened to a narrow or wide casing and to be driven into the face of the 60 casing or hooked over its edge and thus form a self fastening attachment for each spring. It is understood that the brackets are attached near the top of the window frame; and I prefer to connect the spring to the 65 tanged fastening-bar about the middle of

its length, but obviously the spring can be connected to any other point of the bracket desired.

I claim:

1. A bracket of the character described 70 comprising a vertically extending supporting bar, a suspension arm extending at right angles with respect thereto and having that portion in proximity to the bar enlarged to constitute a reinforcement, and a slidable 75 member forming a shade roller fixture adjustably mounted upon the suspension arm, said member embodying a slotted arm and further having the longitudinal edges of its body portion bent upon itself to constitute 80 groove-forming-lips whereby said body portion can be reversibly mounted upon the suspension arm.

2. A bracket of the character described 85 comprising a vertically-extending support- 85 ing bar, a suspension arm extending at right angles with respect thereto and having that portion in proximity to the bar enlarged to constitute a re-inforcement, and a slidable member forming a shade roller fixture ad- 90 justably mounted upon the suspension arm, said member embodying a slotted arm and further having the longitudinal edges of its body portion bent upon itself to constitute groove-forming-lips whereby said body por- 95 tion can be reversibly mounted upon the sus- pension arm, one of said groove-forming-lips of less length than the other.

3. A bracket of the character described comprising a vertically-extending supporting 100 bar, a suspension arm projecting at right angles with respect to said bar, and a slidable member forming a shade roller fixture adjustably mounted upon said arm, said member comprising a body portion and an an- 105 gular extension, said angular extension slotted, said body portion having the longitudinal edges thereof bent upon itself to constitute a pair of groove-forming lips whereby said body portion can be reversibly mounted 110 upon said suspension arm.

4. A bracket of the character described comprising a vertically-extending supporting bar, said bar having a plurality of fastening tangs projecting from one face thereof and further provided with a plurality of fastening tangs projecting from one edge thereof, a sus- 115 pension arm projecting at right angles with respect to said bar, and a slidable member forming a shade roller fixture adjustably mounted upon said arm, said member comprising a body portion and an angular ex- 120 tension, said angular extension slotted, said body portion having the longitudinal edges thereof bent upon itself to constitute a pair 125 of groove-forming-lips whereby said body portion can be reversibly mounted upon said suspension arm.

5. A bracket of the character described comprising a vertically-extending supporting 130

bar, said bar having a plurality of fastening tangs projecting from one face thereof and further provided with a plurality of fastening tangs projecting from one edge thereof, said bar further having an apertured lug projecting from the other edge thereof for attaching a spring thereto, a suspension arm projecting at right angles with respect to said bar, and a 5 slidable member forming a shade roller fixture adjustably mounted upon said arm, said member comprising a body portion and an angular extension, said angular extension slotted, said body portion having the longitudinal edges thereof bent upon itself to constitute 10 a pair of groove-forming-lips whereby said body portion can be reversibly mounted upon said suspension arm.

6. A bracket of the character described comprising a vertically-extending supporting bar, a suspension arm formed integral with the lower end thereof and extending at right angles with respect thereto, a pole supporting arm formed integral with the upper end of said bar and extending at right angles with 20 respect thereto, the pole supporting arm further extending at right angles with respect to the suspension arm and having its free end formed in a curvilinear manner to constitute a seat, said pole supporting arm torsionally twisted intermediate the ends thereof, thereby causing the bottom of said seat to extend at an angle with respect to the inner portion of the arm, and a slidable member forming a shade roller fixture adjustably 25 mounted upon the suspension arm, said member embodying a body portion and a slotted angular extension, said body portion having the longitudinal edges bent upon itself to constitute a pair of groove-forming-lips whereby said body portion is reversibly 30 mounted upon said suspension arm.

35 7. A bracket of the character described comprising a vertically-extending supporting bar, said bar having projecting from one face thereof a plurality of fastening tangs, a suspension arm formed integral with the lower end thereof and extending at right angles with respect thereto, a pole supporting arm formed integral with the upper end of said 40 bar and extending at right angles with respect thereto, the pole supporting arm further extending at right angles with respect to the suspension arm and having its free end formed in curvilinear manner to constitute a seat, said pole supporting arm torsionally twisted intermediate the ends thereof, thereby causing the bottom of said seat to extend at an angle with respect to the inner portion of the arm, and a slidable member 45 forming a shade roller fixture adjustably mounted upon the suspension arm, said member embodying a body portion and a slotted angular extension, said body portion having the longitudinal edges bent upon itself to constitute a pair of groove-forming-lips whereby said body portion is reversibly 50 mounted upon said suspension arm.

55 8. A bracket of the character described comprising a vertically-extending supporting bar, said bar having projecting from one face and from one side edge a plurality of fastening tangs and from its other side edge an apertured lug for connecting a spring thereto, a suspension arm formed integral with the lower end thereof and extending at right angles with respect thereto, a pole-supporting arm further extending at right angles with respect to the suspension arm and having its free end formed in a curvilinear manner to constitute a seat, said pole-supporting arm torsionally twisted intermediate the ends thereof, thereby causing the bottom of said seat to extend at an angle with respect to the inner portion of the arm, and a slidable member forming a shade roller fixture adjustably mounted upon the suspension arm, said member embodying a body portion and a slotted angular extension, said body portion having the longitudinal edges bent upon itself to constitute a pair of groove-forming-lips whereby said body portion is reversibly 60 mounted upon said suspension arm.

65 9. A bracket of the character described comprising a vertically-extending supporting bar, a suspension arm formed integral therewith and projecting therefrom at right angles with respect thereto, a pole-supporting arm projecting at right angles from the top of said bar and having its outer end torsionally twisted and curved to form a seat, and a slidable member constituting a shade roller fixture adjustably mounted upon said suspension arm, said member embodying a body portion and a slotted angular extension, said body portion having the longitudinal edges bent upon itself to constitute a pair of groove-forming-lips whereby said body portion is reversibly 70 mounted upon said suspension arm.

75 10. A bracket of the character described comprising a vertically-extending supporting bar, a suspension arm formed integral therewith and projecting therefrom at right angles with respect thereto, a pole supporting arm projecting at right angles from the top of said bar and having its outer end torsionally twisted and curved to form a seat, and a slidable member constituting a shade roller fixture adjustably mounted upon said suspension arm, said member embodying a body portion and a slotted angular extension, said body portion having the longitudinal edges bent upon itself to provide a pair of groove-forming-lips whereby said body portion is slidably and reversibly mounted upon said suspension arm.

80 11. A bracket of the character described comprising a vertically-extending supporting bar, a suspension arm formed integral therewith and projecting therefrom at right angles with respect thereto, a pole supporting arm projecting at right angles from the top of said bar and having its outer end torsionally twisted and curved to form a seat, and a slidable member constituting a shade roller fixture adjustably mounted upon said suspension, said member embodying a body portion and a slotted angular extension, said body portion having the longitudinal edges bent upon itself to provide a pair of groove-forming-lips whereby said body portion is slidably and reversibly mounted upon said suspension arm, and said supporting bar provided throughout one face with a plural- 85

ity of fastening tangs and further having fastening tangs projecting from one edge.

11. A bracket of the character described comprising a vertically-extending supporting bar, a suspension arm formed integral with the lower end thereof and extending at right angles with respect thereto, a pole supporting arm formed integral with the upper end of said bar and extending at right angles with respect thereto, the pole supporting arm further extending at right angles with respect to the suspension arm, said pole supporting arm having its free end formed in a curvilinear manner to constitute a seat, said pole supporting arm torsionally twisted intermediate the ends thereof thereby causing the bottom of said seat to extend at an angle with respect to the inner portion of the arm, and a shade roller fixture mounted upon the suspension arm.

torsionally twisted intermediate the ends 35 thereof thereby causing the bottom of said seat to extend at an angle with respect to the inner portion of the arm, and a shade roller fixture mounted upon the suspension arm.

13. A bracket of the character described comprising a vertically-extending supporting bar, said bar having projecting from one face and from one side edge a plurality of fastening tangs and from its other side edge an apertured lug for connecting a spring thereto, a suspension arm formed integral with the lower end thereof and extending at right angles with respect thereto, a pole supporting arm formed integral with the upper end of said bar and extending at right angles 55 with respect thereto and further extending at right angles with respect to the suspension arm and having its free end formed in a curvilinear manner to constitute a seat, said pole supporting arm torsionally twisted intermediate the ends thereof thereby causing the bottom of said seat to extend at an angle with respect to the inner portion of the arm, and a shade roller fixture carried by the suspension arm.
